(57) **CLAIM**

The ornamental design for a flame distributor assembly for the cooking surface of a gas stove, as shown and described.

DESCRIPTION

FIG. 1 shows a front perspective view of my design for a flame distributor assembly for the cooking surface of a gas stove;

FIG. 2 shows a front elevational view thereof;

FIG. 3 shows a rear elevational view thereof, the left and right sides being the same; and,

FIG. 4 shows a plan view thereof.
